S. KOJIMA,
LETTER SHEET AND SAFETY ENVELOPE,
APPLICATION FILED MAR. 15, 1916.

1,203,362.

Patented Oct. 31, 1916.

Attorney

UNITED STATES PATENT OFFICE.

SHIGEKI KOJIMA, OF INDEPENDENCE, OREGON.

LETTER-SHEET AND SAFETY-ENVELOP.

1,203,362.

Specification of Letters Patent. Patented Oct. 31, 1916.

Application filed March 15, 1916. Serial No. 84,438.

To all whom it may concern:

Be it known that I, SHIGEKI KOJIMA, a citizen of the Empire of Japan, residing at Independence, in the county of Polk and State of Oregon, have invented certain new and useful Improvements in Letter-Sheets and Safety-Envelops, of which the following is a specification, reference being had to the accompanying drawings.

10 This invention relates to stationery, and particularly to letter sheets which are adapted to be folded and sealed so that the exterior of the sheet forms an envelop.

15 The general object of the invention is to provide a very simple and effective letter sheet of this character which when folded is securely sealed and held from accidental unfolding and in which the written matter contained on the inside of the sheet is securely sealed from observation.

20 A further object of the invention is the provision of a letter sheet of this character which may be economically made, which is simple to use, and which is thoroughly effective for the purpose intended.

25 Another object is to provide a letter sheet of the character stated having means upon its inside face whereby bills or other inclosures may be attached to the letter sheet so that they cannot be accidentally detached therefrom when the letter is opened and thus the bill, check or other matter be lost.

Other objects will appear in the course of the following description.

30 My invention is illustrated in the accompanying drawings, wherein:

Figure 1 is an inside face view of a letter sheet constructed in accordance with one form of my invention; Fig. 2 is an inside face view of this same form but with the lateral portions folded upon the main portion; Fig. 3 is a rear view of the completely folded letter sheet; Fig. 4 is a face view of another form of letter sheet; and Fig. 5 is a view showing the same partly folded.

35 In Fig. 1 I show one form of my invention, and in some respects the simplest form. In this form, 10 designates the letter sheet as a whole. This sheet is rectangular in form and has a length greater than its width. The sheet is intended to be folded upon the lines 11, and the middle portion 12 of the sheet will be folded upon the line 13. Coextensive with the middle portion 12 of the sheet is a sealing flap 14. At the junction of this flap with the middle portion of

the sheet there is a row of perforations 15, and the inner face of the sealing flap is coated with adhesive 16. On each side of the middle portion of the envelop are the lateral flaps 17 and 18, each of which is adapted to be folded at its middle upon the line 19, and the flap 17 at its margin is formed with approximately parallel lines of perforations 20 which extend inward from the edge of the flap. Preferably this line of perforations is curved, as at 21, and then extends straight inward. These lines of perforations define a tongue 23. Upon the inner face of the portion 17, though it may be applied to the opposite flap 18, is placed a small portion of adhesive, designated 22, whereby a bill, check or other inclosure may be attached by one corner to one corner of the sheet so that when the sheet is opened the check or bill will not fall out.

40 In the use of this form of the invention the inside face of the letter sheet is written upon and then the sheet 17 is folded over and then the sheet 18 folded over, with the tongue 23 defined between the lines of perforations 20 disposed over the edge of the margin of the portion 18, as illustrated in Fig. 2. Then the folded sheet is again folded upon the lines 13 and 19 and the sealing flap 14 folded over upon the outside of the envelop and sealed. The envelop is addressed in the ordinary manner. When it is desired to open the envelop, the sealing flap is torn across at the line of perforations whereupon the paper may be very readily unfolded. The tongue 23, which overlaps the portion 18, however, resists the unfolding of the sheet, and the ends of this tongue 23 may be provided upon their inner faces with adhesive 24 so that the tongue 23 may be sealed upon the outer face of the portion 18. When the envelop is sealed, as before described, the written contents of the letter is entirely protected from observation and from moisture, accident or harm.

45 In Fig. 4, I show another form of this invention which is in many respects similar to that heretofore described. In this form, the letter sheet 10^a is folded upon the lines 11^a so as to provide a middle portion 13^a. A sealing flap 14^a is coextensive with the middle portion 13^a of the sheet. The middle portion of the sheet including the sealing flap 14^a, is to be folded upon itself three times, the folds being indicated by the lines 12^a. Hence the sealing flap 14^a is not folded

- at its junction with the body of the sheet, but the edge of the sealing flap is formed with a line of perforations 15^a and inward of this line the sealing flap is coated with adhesive 16^a. The ends of the flap are formed with the laterally disposed sealing tabs 25 which are coated with adhesive upon their inner faces and a row of perforations 26 defines the junction of the sealing tab 15 with the flap 14^a. The lateral portions 17^a and 18^a are adapted to be folded upon the lines 19^a, and one of these lateral portions is formed with the inwardly extending lines of perforations 20^a so as to provide a tongue 23^a corresponding to the tongue 23 previously described. One corner of one of the side portions 17^a or 18^a is provided upon its inner face with a small spot of adhesive 22^a whereby a bill or check may be attached to the inner face of the envelop.

In use, after the letter sheet is written upon the side portions 17^a and 18^a are folded over upon the body of the sheet, the tongue 23^a being disposed over the adjacent margin 25 of the opposed side portion 18^a in the manner illustrated in Fig. 5. The sheet is then folded upon the lines 12^a and 19^a and the margin of the sealing flap 14^a is caused to adhere to the body of the sheet. The laterally projecting sealing tabs are then folded over around the ends of the folded sheet and pasted down. The envelop is then ready for addressing.

This second form of the invention contains all the advantages of the other form, and in addition has the advantage of the ends of the combined letter sheet and envelop being sealed by means of sealing tabs, thus preventing the folded letter from being 40 expanded by pressing upon its top and bottom edges. This second construction is more particularly adapted for letter sheets of relatively heavy material and of relatively large size, or letter sheets designed to contain relatively heavy inclosures.

It will be seen that both forms of my invention are adapted to be used in the form of tablets from which the letter sheets may be taken as they are needed. In both of 50 these forms the letter is securely sealed, cannot readily be tampered with, and may be readily folded and unfolded. It will also be seen that in both forms of my invention it is practically impossible to unfold the 55 sheet without either tearing across the perforations of the sealing flap and thus unfold the sheet in the proper way, or else so dam-

age the sheet by attempting to unfold it from the inside that any one who received the letter would know that it had been 60 opened and its contents read. This is rendered particularly difficult by the engagement of one side of the sheet with the tongue 23, the middle longitudinal fold of the sheet extending through to the middle of this 65 tongue rendering it still more difficult to detach the edges of the sheets from each other so as to permit the sheets to be unfolded from the inside.

Having described my invention, what I 70 claim is:

1. An envelop and letter sheet formed to provide an integral front and back, a sealing flap attached to one edge of the front, and side flaps integral with the back and front 75 and disposed to project laterally beyond the ends of the sealing flap, the sheet being adapted to be folded parallel to the sealing flap to form the back of the envelop, one of the side flaps on its margin having two lines 80 of perforations extending inward from the edge of the flap and defining a tongue adapted to be disposed over the edge margin of the opposite side flap when the envelop is folded, the tongue being so disposed that the 85 transverse line upon which the back is folded against the front will extend through the tongue intermediate of the perforations defining it.

2. An envelop and letter sheet formed to 90 provide an integral front and back, a sealing flap attached to one edge of the front, and side flaps integral with the back and front and disposed to project laterally beyond the ends of the sealing flap, the sheet 95 being adapted to be folded parallel to the sealing flap to form the back of the envelop, one of the side flaps on its margin having two lines of perforations extending inward from the edge of the flap and defining a 100 tongue adapted to be disposed over the edge margin of the opposite side flap when the envelop is folded, the tongue being so disposed that the transverse line upon which the back is folded against the front will extend through the tongue intermediate of the 105 perforations defining it, the inner surface of the tongue being coated with adhesive.

In testimony whereof I hereunto affix my signature in the presence of two witnesses. 110

SHIGEKI KOJIMA.
